CHARLES F. BELSHAW, OF DEARBORN, MICHIGAN

ICE REFRIGERATING DEVICE

Application filed November 16, 1929; Serial No. 407,739.

My invention relates to improvements in refrigerators having ice containers together with accessories therefor and the objects of my improvements are, first, to provide an ice refrigerating device akin to the mechanism of the evaporating system of a mechanical refrigerator; second, to provide a refrigerator device unit embodying an ice container, ice rack, drip pan, drain device, and suspension devices; third, to provide an ice refrigerating device capable of being suspended in such manner as to accomplish complete separation of the refrigerating medium from contact with the inner lining of the refrigerator cabinet; fourth, to provide a refrigerating device having the maximum of freedom of air circulation therearound and therethru; fifth, to provide an ice refrigerating device having complete separation from contact with the inner lining of a refrigerator with the exception of its suspension and drainage means; sixth, to provide an ice refrigerating device having an adjustably and readily removable ice basket gate; and seventh, to provide an ice refrigerating device having its component parts readily removable as separate units or as a complete refrigerating unit.

I attain these objects by the mechanism illustrated in the accompanying drawings, in which—

Figure 1 is a front elevation of a refrigerator with its door removed; said refrigerator being equipped with my refrigerating device; Fig. 2, a sectional view of the refrigerator and its refrigerating device, together with its door, taken on the line 2—2; Fig. 1; Fig. 3, a plan view of an ice rack used in my refrigerating device; Fig. 4, a side elevation of the ice rack; Fig. 5, a side elevation of the adjustable ice basket gate as used in my refrigerating device; Fig. 6, an end elevation of the adjustable ice basket gate; Fig. 7, a front elevation of a refrigerator, with its door removed; said refrigerator being equipped with my refrigerating device installed as a "top icer" arrangement; Fig. 8, a sectional view of the refrigerator and its refrigerating device, together with its door, taken on the line 8—8; Fig. 7; Fig. 9, a front elevation of the ice container, ice rack, and

drip pan unit; and Fig. 10, a sectional view of the ice container, ice rack, and drip pan unit taken on the line 10—10, Fig. 9.

In Figs. 1 and 2, a "mechanical" type refrigerator cabinet 1 of a conventional design, having an inner lining or shell 2, is equipped with suspension hanger bolts 3 and a drain outlet socket or connection 4 available for use with my refrigerator device. Fig. 1 shows a front sectional elevation through the refrigerator cabinet 1 having an ice basket or ice container 5 arranged as a "side-icer". The basket 5 is attached to the inner shell 2 of refrigerator cabinet 1 by means of the hanger bolts 3 incorporated in the cabinet construction and by means of typical hanger members 6. The ice container or basket 5 is typically reenforced by a loop or band of metal 7 around the entire top and extending down and across the normally cut-away portion of the front or service side as shown at 8. It is further reenforced around the bottom by a similar metal band 9 which additionally serves as a supporting means for the ice rack 10, engaging said ice rack 10 at its reenforced ends 11. The ice rack 10 is easily removed by lifting upwardly and withdrawing through the ice basket or container 5. Figs. 3 and 4 disclose a plan and side elevation of the ice rack 10 showing its construction as a stamping from a single sheet of metal securing a reenforced slatted or bar type construction at a single operation by means of the depressed openings as at 12. This construction and slatted arrangement permits a maximum of air movement down thru the ice rack 10 and at the same time by the spacing centers used controls the extent to which ice will melt through the ice rack 10 and allows a construction with the complete elimination of fabrication joints or crevices to hamper the tinning or other corrosion preventive processes involved and results in a more sanitary and readily cleaned piece of equipment. Completely encircling the exterior perimeter of the lower edge of the basket 5 adjacent its lower reenforcing band 9 is employed a metal flange 13 normally of right angular cross-section having an outwardly turned top edge or lip 14 and a downwardly turned lower edge 100

or lip 15. The object of employing this flange with its lip projections is to collect ice drip-
page from a relatively larger area than a cross-section of the basket itself and return it to a drip pan having materially smaller area than the area covered by the basket for the primary purpose of securing greater freedom of air circulation through the increased space around the drip pan 18 and inducing an increased amount of air to enter the basket 5 in contact with the ice. The flange 13 is arranged to engage snugly with the exterior surface of basket 5 and is customarily attached and suspended by through bolts and suitable washers engaging through the wire mesh of the basket as at 17 or if desired may be suspended from the reenforcing band 9 of the basket 5.

Attached to the exterior of the flange 13 are straps 16 suitably formed for suspending and spacing the drip pan 18 under the downwardly turned lip 15 of the flange 13 and further providing for the necessary pitch, as disclosed in Figs. 2, 8, and 10 for draining the ice water drippage from the inner surface of the drip pan 18. The drip pan 18 consists essentially of a metallic top surface 19 with a raised lip or edge 20 extending around its perimeter as shown in Figs. 1, 2, 7, 8, 9, and 10. If desired, the drip pan 18 may be constructed with an insulating board over the bottom of the drip pan 18 to prevent condensation and drippage or it may employ an insulating material encased in a secondary bottom metallic shell or may be composed of two metallic shells so spaced as to secure an air space between the metal shells. In any or all designs, the drip pan 18 would be provided with a drain outlet tube 21, which may be integrally fastened to said drip pan 18. Employed in connection with the drain removal device of the drip pan 18, through its drain connection 21, any standard and common type of drain tube and trap might be employed. An improved type of one piece drain tube 22 and full circle "pig-tail" trap 23 has been designed for this purpose to overcome the very slight trapping effect of customary designs and to replace and simplify the four piece drain and trap usually employed. The drain tube 22 and trap 23 being normally constructed of about $\frac{3}{4}$ inch seamless copper tubing, presents a large unrestricted cross section which is not readily clogged due further to the effective static head for emptying the trap 23, said static head extending the entire height of the tube 22. This one piece construction allows ready cleaning by placing under a water faucet and by reversing end for end makes it unnecessary to disassemble and clean by hand, any inner complicated parts.

It has been specifically found by experiment and test that the combination of my equipment above described, both because of

the general open nature of the construction used and the clearance tolerances provided, have accomplished a maximum of air circulation resulting in an average temperature differential within the food compartment of 7 degrees as against 10 to 14 degrees in ice refrigerators of standard and common design. This also results in an average relative humidity of air in the food compartment of from 75 to 80 percent as against 90 to 95 percent prevalent in standard makes, grades, and corresponding sizes of ice refrigerators. Also the temperature of the food compartment has been lowered by the freedom of air circulation to a point of securing average "maximum food compartment temperatures" all below 50 degrees, when the outside temperatures do not exceed 90 degrees and a well built cabinet using the equivalent of 2" of cork is employed. Such results have never been commercially before attained and constitute a marked departure in the conception of ice refrigeration and virtually entitles consideration of the construction described as a distinct type of ice refrigerating mechanism. In addition to the attainment of lower temperatures, relative humidities, and variation of temperature within the food compartment, there is the further saving of an average of 15 percent in the ice melting rate due to the complete separation of the ice cooling medium from intimate contact with the inner lining of the refrigerator.

From a study of the design it will readily be seen that the drain 22 and trap 23, the drip pan 18, and the ice rack 10, are all instantly removable for cleaning and allow complete access to all surfaces of the basket 5, for cleaning. When desired the shell of the basket 5 itself may be readily arranged for removal by simple unhooking from its hanger members 6 or the removal of the nuts 41 attaching the hanger members 6 to the refrigerator cabinet lining or shell 2. The entire mechanism being normally of heavily tinned finish presents a new departure in improved appearance and sanitation. Employing a four sided construction the permanently fixed front 42 allows the retention of left over pieces upon re-icing of the refrigerator and does away largely with the objection to ice refrigeration due to aiding in the elimination of objectionable drippage, etc. incident to the customary removal of left over pieces, the placing of the fresh charge, and the replacement of the original small pieces. This feature also will lessen by 50 per cent the time usually required in the house for servicing by the ice deliveryman.

As an accessory to facilitate the use of certain shapes and heights of baskets a detachable gate or shield 24 is supplied as illustrated in Figs. 5, 6, 9, and 10. The ice gate 24 is so formed as to provide a guide tube 43 along its top edge for retaining sliding

plungers or pins 25. The plungers 25 are provided with right angular lugs 26 extending through slotted apertures in the guide tube portion 43 along the top edge of the ice gate 24 so as to be readily controlled by hand for placement or removal at or from any desired place at the front of the open portion of the ice container basket 5. The lower surface of the extending ends of plungers 25 are notched, as at 27, for engaging with the wire mesh of basket 5 and provides means for retention in place without the employment of complicated devices. The location of the ice retaining gate 24 is illustrated in its elevated position in Fig. 10 and is so placed only when necessary to retain a maximum number of pieces or quantity of ice to avoid drippage outside the basket 5 due to proportionately large quantities of heat supplied at the front of the refrigerator frequently causing the ice to melt over the open front portion of the basket 5. When the quantity of ice is reduced, the gate 24 may be lowered to any desired height at will or completely lowered down out of the way as at 29, Fig. 10, hidden behind the permanently closed portion of basket 5 and protected by the reenforcing band 8, during the reicing operation. At the option of the user it may be removed at will and may be dispensed with in the more shallow designs of baskets, such as top-icer arrangements shown in Figs. 7 and 8.

In side icer arrangements of the basket 5, the use of the outwardly turned lip 14 of flange 13, with the large open area through the ice rack 10 and above and around drip pan 18, a great amount of air is induced to pass through the charge of ice in the basket 5, thus acting as a baffling arrangement as well as for drip collection purposes. The uniform spilling of cold air down around all sides of the drip pan 18 assures almost perfect distribution of cold air and in the complete elimination of "dead corners" or pockets of fouled air. In effect there is accomplished in the way of circulation that which is normally attendant only with the use of heavily insulated baffles dividing the food and ice compartments of a refrigerator. The omission of such baffles, possible with my design, saves in the cost of construction and results in a more pleasing appearance and a more sanitary refrigerator. Experiments have shown that no particular advantage accrues from the use of a baffle with my design. Figs. 7 and 8 illustrates substantially the same equipment as heretofore described arranged as a "top icer" refrigerator. In this case the same standard type of drip collection means is employed as in the side icer, the drip-pan serving to more sharply divide the refrigerator into food and ice compartments. Due to the entry of the vast majority of heat into the front and around the doors of a

refrigerator there is a natural updraft at the front and downdraft at the rear of the simple top icer arrangement illustrated. This circulation is further augmented by the insulated drip pan and the slope of same toward the rear of the refrigerator for drip removal at the rear.

In the development of ice containers or "baskets" for use with existing standard types of ice refrigerators an entirely new conception of ice refrigeration was secured and the possibilities of the development of my ice refrigerating device, akin to a mechanism such as the evaporating system of a mechanical refrigerator, was conceived. Such a mechanism for utilizing the full refrigerating effect of ice at 32 degrees embodies not only the basket or container for the ice but the combination of it with specific types of ice racks, drip pans, drain devices, hanger devices and arrangement details as to clearances for the setting up of extreme freedom of air circulation. Such a refrigerating mechanism contemplates usage in conjunction with the simplest type of "mechanical" refrigerator cabinet devoid of all inner partitions, baffles, drain devices, etc. Such a cabinet design allows for one piece inner lining of simplest design, extreme sanitation, and an economy of construction. My new device contemplates complete separation of the refrigerating medium from contact with the inner lining of the refrigerator cabinet, the only attachment or contact points being in the suspension means of the basket assembly and the drain tube contact.

The insulating material 48 is assembled between the inner lining 2 and the outer shell 1. In Figs. 2 and 8, the door 49 with its inner lining 50, its outer lining 51, its insulating material 52, its door frame 53, and its gasket sealing material 54 is shown as assembled in position on hinges (not shown). The upper insulated portion of the refrigerator is disclosed as being mounted on the uninsulated ventilated storage chamber 55 as a refrigerator base. The storage chamber 55 is disclosed as being equipped with the shelf 56 extending for a portion of the distance between the lowered front screen 57 and the wire screen 58 at the rear of said storage chamber 55. The shelf 56 may be provided with an upturned portion 59 to prevent spilling of the contents over its rear edges. The open space 60 between the upturned portion 59 of the shelf 56 and the wire screen 58, together with the drain 61 in the floor 62, serve for the purpose of a permanent drain to the sewer for the removal of the ice meltage from the refrigerator or the drip from the mechanical evaporator.

The drain tube 22 has its lower end 63 loosely fitted into the hole 64, in the inner lining 2, said hole 64 being further connected with the threaded connection 65 which extends

through the insulating material 48 and the outer shell 1 and which is further hermetically sealed relative to the insulating material 48 and the outer shell 1 by the gasket 66 and the nut 67.

It is to be noted that the drain outlet tube 21 is loosely entered into the drain tube 22 which has, in turn, its end 63 loosely entered into the hole 64, thus permitting the easy removal of the drain tube 22 by telescopically sliding said drain tube 22 upwardly over the drain outlet tube 21 attached to the drip pan 18 until the lower end 63 of the drain tube 22 is free of the hole 64.

15 The drip pan 18 is provided with a plurality of lugs 68 to straddle engage one or more of the straps 16 to properly position said drip pan 18 after it has been moved over the straps 16 and into its fixed position on 20 the straps 16 and under the ice basket 5.

It is to be further understood that the refrigerator cabinet with its inner lining 2, its outer shell 1, its insulating material 48 together with the storage space 55 and its accessories was disclosed in my application for U. S. Letters Patent bearing Serial No. 395,050 and is further disclosed in this application merely to show the general relation of such a refrigerator cabinet to the application 30 of the ice refrigerating device which forms the basis of my claims in this application.

I claim:

1. In an ice refrigerating device, the combination of an ice container having a frame member, a removable ice rack supported on the frame member of said ice container, a right angular member extending around the lower side of said ice container, said right angular member having an upwardly and an outwardly extending lip beyond said ice container, said right angular member being further provided with a downwardly and an inwardly extending lip within the area of the lower side of said ice container, said right angular member being further suitably attached to said ice container, downwardly and inwardly extending brackets suitably attached to said right angular member at points outside of its downwardly and inwardly extending lip, and a removable drip pan supported on said downwardly and inwardly extending brackets, said removable drip pan having a drain outlet, and a removable drain member suitably supported, said removable drain member having a complete convolution of itself between its ends, said removable drain member encircling the drain outlet of said drip pan.

2. In an ice refrigerating device, the combination of an ice container suitably supported, a removable ice rack supported on said ice container, a removable drip pan supported below said ice container, said removable drip pan having a drain outlet, and a removable drain member adapted to encir-

cle the drain outlet of said removable drip pan, said removable drain member being provided with a complete convolution of itself between its ends.

3. In an ice refrigerating device, the combination of an ice container and a right angular member extending around the lower perimeter of said ice container, said right angular member having a collecting flange beyond said ice container, said right angular member being further provided with an angular flange extending within the area of the lower side of said ice container, said angular drainage flange being provided with a downwardly extending portion terminating in a drainage opening.

4. In an ice refrigerating device, the combination of an ice container having one of its sides of lesser height than the total height of said ice container and a removable gate for closing the open portion of the side of said ice container having a lesser height than the total height of said ice container.

5. In an ice refrigerating device, the combination of an ice container having one of its sides open for a portion of its height and a gate for adjustably closing the open portion of one of the sides of said ice container, said gate being adjustably supported on said ice container.

6. In an ice refrigerating device, the combination of an ice container having one of its sides open for a portion of its height and a gate for closing the open portion of said ice container, said gate being capable of being adjustably supported behind said side of said ice container which is open for a portion of its height.

7. In an ice refrigerating device, the combination of an ice container having apertures and a gate having adjustable members, the adjustable members of said gate having notches for engaging the apertures of said ice container.

8. In an ice refrigerating device, the combination of an ice basket, a closure member, plungers slidably mounted in said closure member, said plungers being provided with notches for engaging said ice basket, said plungers being further provided with handles for slidably operation thereof.

9. In an ice refrigerating device, the combination of an ice container comprising apertured side walls, a frame member extending around the perimeter of the lower side of said ice container, said frame member extending inwardly from the inner wall surfaces of said ice container, and a removable ice rack having rolled ends supported on said frame member, said removable ice rack having its rolled ends contacting with the side walls of said ice container.

CHARLES F. BELSHAW.
